UNITED STATES PATENT OFFICE.

JESUS ALVA ROMANO AND ERNEST ALBERT BARTON, OF CELAYA,
GUANAJUATO, MEXICO.

FLY-WHEEL-CLUTCHING DEVICE.

SPECIFICATION forming part of Letters Patent No. 392,759, dated November 13, 1888.

Application filed May 1, 1888. Serial No. 272,412. (No model.)

To all whom it may concern:

Be it known that we, JESUS ALVA ROMANO and ERNEST ALBERT BARTON, of Celaya, State of Guanajuato, Mexico, have invented 5 a new and Improved Fly-Wheel-Clutching Device for Sewing Machines, of which the following is a full, clear, and exact description.

Our invention relates to an automatic loose and fast attachment for sewing-machines, and 10 has for its object to render their manipulation more convenient and less troublesome, and also to provide a means whereby the fly-wheel may be made to revolve with the shaft in one direction and independently thereof when 15 turned in a contrary direction, and also whereby the said fly-wheel may be virtually disconnected from the driving-shaft of the machine, so as to turn independent of the said shaft in either direction.

20 The invention consists in the construction and combination of the several parts, as will be hereinafter fully set forth, and pointed out in the claims.

Reference is to be had to the accompanying 25 drawings, forming a part of this specification, in which similar figures of reference indicate corresponding parts in all the views.

Figure 1 is a side elevation of a portion of the fly-wheel attached to the shaft. Fig. 2 is 30 a vertical section on line 2 2 of Fig. 1. Fig. 3 is a transverse section on line 3 3 of Fig. 2. Fig. 4 illustrates, respectively, a front elevation, a side view, and a bottom plan view, of the locking-bolt. Fig. 5 illustrates, respectively, a front and side elevation of the latch; and Fig. 6 is a partial plan view of the shaft, 35 illustrating the location of the aperture therein adapted to receive the latch.

The drive-shaft 10 is provided with a dia- 40 metrical aperture, 11, which aperture for the greater portion of its length is rectangular, as shown in Fig. 6, and at one end circular and interiorly threaded, as shown at 12, and stopped with a screw, 13. In the aperture 11 45 a latch, 14, is held, consisting of a head, 15, beveled upon one face, as shown in Fig. 5, and a shaft, 16, which shaft is surrounded by a spiral or coil spring, 17, bearing, respectively, upon the screw 13 and on the face of the latch- 50 head, as best shown in Fig. 2.

The hub of the fly-wheel 18, which is mounted upon the shaft 10, is provided upon the inner face with a horizontal groove, 19, extending through from side to side, and an opening, 20, in the outer surface at the outer end, which opening 55 intersects with the groove 19. Within the groove 19 and opening 20 a locking-bolt, 21, is held to slide, which locking-bolt is preferably angular, the horizontal member sliding in the groove 19 and the vertical member in 60 the opening 20. As will be seen by reference to Fig. 4, the locking-bolt is provided at the extremity of its horizontal member with an inclined or beveled surface, 22, adapted to engage the inclined surface of the latch-head, 65 the two inclinations being made, preferably, at an angle of forty-five degrees.

The fly-wheel is secured upon the drive-shaft 70 through the medium of a binding-plate, 23, which plate engages the outer end of the shaft and the outer surface of the fly-wheel hub, being secured to the former by means of a set-screw, 24, and smaller screws, 25, if so desired.

In the operation of our invention, when the 75 fly-wheel is turned from right to left it will also communicate motion to the drive-shaft 10, as the side wall of the groove 19, coming in contact with the perpendicular face of the latch-head, binds against the same, and through the 80 medium of the said latch the shaft is rotated in unison with the wheel. If, on the contrary, the fly-wheel is turned from left to right as the wheel revolves, the opposite wall of the groove 19, coming in contact with the beveled 85 surface of the latch-head, presses the said latch against the action of the spring downward in the aperture 11, and the fly-wheel is allowed to revolve free of the shaft, and then the attachment for winding thread on a bobbin or 90 spool may be applied without having to take off the sewing or band or look after threads, &c., as in other sewing-machines.

When it is desired to revolve the fly-wheel and not manipulate these several operative parts 95 of the machine, the locking-bolt 21 is pressed inward, and the beveled extremity of the horizontal member, being brought in contact with the beveled face of the latch, presses the latter down in its aperture, and the locking-bolt, 100

passing over the aperture to the inner extremity of the groove 19, retains the latch within its aperture and permits the fly-wheel, as revolved, to turn freely upon the shaft with-
5 out in the least affecting the same.

It will be observed that the various parts of this invention are simple in construction and not liable to get out of order, and may be readily manipulated by the most inexperienced
10 person.

Having thus fully described our invention, we claim as new and desire to secure by Letters Patent—

1. The combination, with the driving-shaft
15 of a sewing-machine provided with a diametrical aperture closed at one end, and a spring-actuated latch having a beveled head held in said aperture, of a fly-wheel held to revolve upon said shaft, provided with a horizontal
20 groove in the inner face of its hub, and an intersecting vertical opening at the front of said hub, and a locking-bolt sliding in said groove and opening, provided with a beveled ex-

tremity adapted to engage the beveled surface of the latch, substantially as shown and de-
25 scribed.

2. The combination, with the driving-shaft of a sewing-machine, provided with a diametrical aperture closed at one end, and a spring-
30 actuated latch having a beveled head held in said aperture, of a fly-wheel revolving upon said shaft, provided with a horizontal groove in the inner face of its hub, and a vertical opening intersecting said groove, an angular locking-bolt sliding in said groove and open-
35 ing, having a beveled extremity to engage the head of the latch, a binding-plate engaging the shaft and wheel-hub, and a set-screw se-
curing the said plate to the shaft, substantially as shown and described, and for the purpose 40 herein set forth.

JESUS ALVA ROMANO.

ERNEST ALBERT BARTON.
